(57) **ABSTRACT**

A conformance control method includes identifying a target location of a wellbore formed from a terranean surface to two subterranean formations that include a high permeability formation having a first permeability and a low permeability formation having a second permeability that is equal or less than one-third of the first permeability. The method includes forming a first plurality of tunnels in the high permeability formation from the wellbore; injecting, into the high permeability formation and the low permeability formation, a chemical fluid from the wellbore through the first plurality of tunnels; expanding a sweep area of the injected chemical fluid by injecting the chemical fluid into the high permeability formation through the first plurality of tunnels; forming a second plurality of tunnels in the low permeability formation from the wellbore; and increasing a contact area of an injection fluid in the low permeability formation with the second plurality of tunnels.

**SYSTEMS AND METHODS FOR
CONFORMANCE CONTROL OF A
WELLBORE**

TECHNICAL FIELD

This disclosure relates to systems and methods for conformance control of a wellbore.

BACKGROUND

Oil production with high water cut is a well-recognized problem in the oil industry and reducing water cut has become an important target for oilfield operators. High water cut not only increases the cost of oil production, but from the source, high water cut is closely related to poor conformance control and lower sweeping efficiency of an injection well, especially for a reservoir dependent on the injection water to maintain reservoir energy. There are many technologies and methods that can be used to improve sweep efficiency and reduce water channeling. From the operation cycle, it can be divided into fluid flooding and improvement treatment. Fluid flooding refers to the continuous injection of displacing fluids into the formation to displace oil (with a total injection volume typically greater than 5% of the reservoir and/or well-pattern pore volume), such as polymer flooding, surfactant/polymer flooding and foam flooding.

Through these techniques, there is an increase of viscosity of the displacing fluid for improving the mobility ratio of the displacing fluid to the oil being displaced. Improvement treatment means implementing a measure on an injection or production well to reduce water production. Technologies implementing on injection wells are called conformance control, while technologies implementing on production wells are named as water shutoff. The objective of these technologies is to change the flow path of injection water.

SUMMARY

In an example implementation, a conformance control method includes identifying a target location of a wellbore formed from a terranean surface to at least two subterranean formations. The at least two subterranean formations include a high permeability formation having a first permeability and a low permeability formation having a second permeability that is equal or less than one-third of the first permeability. The method includes forming, with a radial jet drilling assembly, a first plurality of tunnels in the high permeability formation from the wellbore; injecting, into the high permeability formation, a chemical fluid from the wellbore through the first plurality of tunnels; expanding a sweep area of the injected chemical fluid by injecting the chemical fluid into the high permeability formation through the first plurality of tunnels; forming, with the radial jet drilling assembly, a second plurality of tunnels in the low permeability formation from the wellbore; and increasing a contact area of an injection fluid in the low permeability formation with the second plurality of tunnels.

In an aspect combinable with the example implementation, each of the first plurality of tunnels is 1-2 inches in diameter and between 100 and 700 feet in length from the wellbore.

In another aspect combinable with one, some, or all of the previous aspects, each of the second plurality of tunnels is 1-2 inches in diameter and between 100 and 700 feet in length from the wellbore.

2

In another aspect combinable with one, some, or all of the previous aspects, the chemical fluid includes a gel.

In another aspect combinable with one, some, or all of the previous aspects, the chemical fluid includes swellable particles.

Another aspect combinable with one, some, or all of the previous aspects includes logging the wellbore.

Another aspect combinable with one, some, or all of the previous aspects includes identifying the target location 10 based at least in part on a log of the wellbore generated by the logging.

Another aspect combinable with one, some, or all of the previous aspects includes injecting the injection fluid into the wellbore subsequent to forming the second plurality of 15 tunnels in the low permeability formation.

In another aspect combinable with one, some, or all of the previous aspects, the first plurality of tunnels includes between 2 and 8 tunnels.

In another aspect combinable with one, some, or all of the 20 previous aspects, the second plurality of tunnels includes between 2 and 8 tunnels.

In another aspect combinable with one, some, or all of the previous aspects, a volume of the injected chemical fluid 25 includes between 0.02 and 0.10 pore volume of the high permeability formation.

Another aspect combinable with one, some, or all of the previous aspects includes isolating, with a temporary zonal isolation device, the low permeability formation from the wellbore prior to injecting the chemical fluid from the 30 wellbore through the first plurality of tunnels.

In another example implementation, a well system 35 includes a wellbore formed from a terranean surface to a target location including at least two subterranean formations. The at least two subterranean formations include a high permeability formation having a first permeability and a low permeability formation having a second permeability that is equal or less than one-third of the first permeability. The system includes a radial jet drilling assembly configured to perform operations including forming a first plurality of 40 tunnels in the high permeability formation from the wellbore; and subsequent to an injection of a chemical fluid, forming a second plurality of tunnels in the low permeability formation from the wellbore. The system includes a fluid injection system configured to inject the chemical fluid into 45 the high permeability formation from the wellbore through the first plurality of tunnels. A sweep area of the injected chemical fluid is expanded by injecting the chemical fluid into the high permeability formation through the first plurality of tunnels, and a contact area of an injection fluid is 50 increased in the low permeability formation with the second plurality of tunnels.

In an aspect combinable with the example implementation, each of the first plurality of tunnels is 1-2 inches in diameter and between 100 and 700 feet in length from the 55 wellbore.

In another aspect combinable with one, some, or all of the previous aspects, each of the second plurality of tunnels is 1-2 inches in diameter and between 100 and 700 feet in length from the wellbore.

In another aspect combinable with one, some, or all of the previous aspects, the chemical fluid includes a gel.

In another aspect combinable with one, some, or all of the previous aspects, the chemical fluid includes swellable particles.

Another aspect combinable with one, some, or all of the previous aspects includes a logging system configured to 65 perform injection profile logging of the wellbore.

In another aspect combinable with one, some, or all of the previous aspects, the target location is identified based at least in part on a log of the wellbore generated by the logging system.

In another aspect combinable with one, some, or all of the previous aspects, the fluid injection system is configured to inject an injection fluid into the wellbore subsequent to the formation of the second plurality of tunnels in the low permeability formation.

In another aspect combinable with one, some, or all of the previous aspects, the first plurality of tunnels includes between 2 and 8 tunnels.

In another aspect combinable with one, some, or all of the previous aspects, the second plurality of tunnels includes between 2 and 8 tunnels.

In another aspect combinable with one, some, or all of the previous aspects, a volume of the injected chemical fluid includes between 0.02 and 0.10 pore volume of the high permeability formation.

Another aspect combinable with one, some, or all of the previous aspects includes a temporary zonal isolation device positioned in the wellbore to fluidly isolate the low permeability formation from the wellbore prior to injection of the chemical fluid from the wellbore through the first plurality of tunnels.

Implementations of a systems and methods for well conformance control according to the present disclosure may include one or more of the following features. For example, implementations according to the present disclosure can treat both high and low permeability zones in a single downhole operation by increasing a water intake capacity of the low permeability zones while reducing the water intake capacity of the high permeability zones.

The details of one or more implementations of the subject matter described in this disclosure are set forth in the accompanying drawings and the description below. Other features, aspects, and advantages of the subject matter will become apparent from the description, the drawings, and the claims.

BRIEF DESCRIPTION OF THE DRAWINGS

FIG. 1 is a schematic diagram of an example well system that includes multiple tunnels formed in subterranean formations to treat both high and low permeability formations according to the present disclosure.

FIG. 2A is another schematic diagram of the example well system of FIG. 1 according to the present disclosure.

FIG. 2B is another schematic diagram of a portion of the example well system of FIG. 1 according to the present disclosure.

FIG. 3 is a flowchart that shows an example method for treating both high and low permeability formations according to the present disclosure.

FIGS. 4A and 4B are virtual geological models of a well system that includes multiple tunnels formed in subterranean formations to treat both high and low permeability formations according to the present disclosure.

FIGS. 5-8 are graphs that illustrate water cut comparisons in a well system includes multiple tunnels formed in subterranean formations to treat both high and low permeability formations according to the present disclosure.

DETAILED DESCRIPTION

The present disclosure describes implementations of a well system and methods for treat both high and low

permeability formations that include multiple tunnels formed in the formations from a wellbore. In example implementations, systems and methods according to the present disclosure provide an integrated approach to treat high permeability and low permeability zones (i.e., subterranean formations or reservoirs) together to maximize a synergistic effect. Example implementations of a well system include a primary (for example, vertical) wellbore from which multiple tunnels are formed through both a high permeability zone that surrounds a portion of the wellbore (at a particular depth) and a low permeability zone that surrounds another portion of the wellbore (at another, different particular depth).

The tunnels can be formed, for example, by radial jet drilling and can be formed in a particular sequential order. For example, a first operation can include forming (for example, with the radial jet drilling) lateral (for instance, horizontal) tunnels from the primary wellbore in one or more high permeability zones. Subsequently, one or more chemicals can be injected from the tunnels into the one or more high permeability zones. The one or more chemicals can be allowed to migrate deeper from the one or more high permeability zones. In some aspects, the one or more chemicals include gels, swellable particles and fibers, or other materials that can be trapped in areas of high permeability zones to reduce the (relatively high) permeability

A second operation can include forming (for example, with the radial jet drilling) lateral (for instance, horizontal) tunnels from the primary wellbore in one or more low permeability zones. The one or more tunnels in the low permeability zones can increase a contact area of injected water into the low permeability zone(s) to improve a sweeping area.

As shown, the well system 10 accesses a subterranean formation 40, and provides access to hydrocarbons located in such subterranean formation 40. In an example implementation of system 10, the system 10 may be used for a drilling operation as well as a completion operation to enhance a production of hydrocarbons through a wellbore tubular string. For example, the well system 10 can include a fluid injection system 19 that, among other operations can inject a fluid 21 into the wellbore 20. Fluid 21 can represent a chemical fluid (such as a gel or gel with swellable particles) that is injected as part of a conformance control method as described here. Fluid 21 can also represent an injection fluid (such as water) used in a water flooding operations.

As illustrated in FIG. 1, an implementation of the well system 10 includes a drilling assembly (or “assembly”) 15 deployed on a terranean surface 12. The assembly 15 can generally represent a drilling assembly that can be used to form the wellbore 20 extending from the terranean surface 12 and through one or more geological formations in the Earth, as well as tunnels 70a and tunnels 70b that are formed from the wellbore 20 into subterranean formations 40 and 42 located under the terranean surface 12. One or more wellbore casings, such as a surface casing 30 and intermediate casing 35, may be installed in at least a portion of the wellbore 20 (for example subsequent to completion of the drilling operation or some other time).

In some embodiments, the assembly 15 may be deployed on a body of water rather than the terranean surface 12. For instance, in some embodiments, the terranean surface 12 may be an ocean, gulf, sea, or any other body of water under which hydrocarbon-bearing formations may be found. In short, reference to the terranean surface 12 includes both

land and water surfaces and contemplates forming and developing one or more well systems **10** from either or both locations.

Generally, as a drilling system, the assembly **15** may be any appropriate assembly or drilling rig used to form wellbores or boreholes in the Earth. The assembly **15** may use traditional techniques to form such wellbores, such as the wellbore **20** and tunnels **70a** and **70b**, or may use nontraditional or novel techniques. In some embodiments, the drilling assembly **15** may use rotary drilling equipment to form the wellbore **20** and other, non-rotary drilling techniques (i.e., techniques that do not use a rotating drill bit) to form the tunnels **70a** and **70b**. Rotary drilling equipment is known and may consist of a drill string and a drill bit (or bottom hole assembly that includes a drill bit). In some embodiments, the assembly **15** may consist of a rotary drilling rig. Rotating equipment on such a rotary drilling rig may consist of components that serve to rotate a drill bit, which in turn forms a wellbore, such as the wellbore **20**, deeper and deeper into the ground. Rotating equipment consists of a number of components (not all shown here), which contribute to transferring power from a prime mover to the drill bit itself. The prime mover supplies power to a rotary table, or top direct drive system, which in turn supplies rotational power to the drill string. The drill string is typically attached to the drill bit (for example, as a bottom hole assembly). A swivel, which is attached to hoisting equipment, carries much, if not all of, the weight of the drill string, but may allow it to rotate freely.

The non-rotary techniques can include, for example, laser drilling or radial jet drilling techniques, among others. For example, in examples in which the diameter of the wellbore **20** (as a primary wellbore **20**) is greater than the diameter of the tunnels **70a** and **70b**, radial jet drilling can be an effective, environmentally friendly method to drill small-diameter horizontal tunnels (tunnels **70a** and **70b**) from a vertical or near-vertical wellbore (wellbore **20**) using a coiled tubing unit. Radial jet drilling can eliminate a need for a conventional bit and drilling mud by substituting such drilling features with a high-pressurized fluid that is circulated through forward and backward nozzles connected to a high pressure hose. The pressurized fluid ejected from the forward nozzles is used to erode and, therefore, "drill" a subterranean formation, while the fluid leaving the backward nozzles is used to push the nozzle forward and to widen the diameter of the formed tunnels.

In some embodiments of the well system **10**, the wellbore **20** may be cased with one or more casings. As illustrated, the wellbore **20** includes a conductor casing **25**, which extends from the terranean surface **12** shortly into the Earth. A portion of the wellbore **20** enclosed by the conductor casing **25** may be a large diameter borehole. Additionally, in some embodiments, the wellbore **20** may be offset from vertical (for example, a slant wellbore). Even further, in some embodiments, the wellbore **20** may be a stepped wellbore, such that a portion is drilled vertically downward and then curved to a substantially horizontal wellbore portion. Additional substantially vertical and horizontal wellbore portions may be added according to, for example, the type of terranean surface **12**, the depth of one or more target subterranean formations, the depth of one or more productive subterranean formations, or other criteria.

Downhole of the conductor casing **25** may be the surface casing **30**. The surface casing **30** may enclose a slightly smaller borehole and protect the wellbore **20** from intrusion of, for example, freshwater aquifers located near the terranean surface **12**. The wellbore **20** may then extend vertically

downward. This portion of the wellbore **20** may be enclosed by the intermediate casing **35**.

As shown in this example, a wellbore tubular **17** is run into the wellbore **20** (whether cased or not). The wellbore tubular **17** is coupled to a bottom hole assembly (BHA) **55**. In the case of forming the wellbore **20** (and, optionally, the tunnels **70a** and **70b**), the wellbore tubular **17** can be a drill string and the BHA **55** can include a drill bit. In some aspects, wellbore tubular **17** can represent a drill string with a drill bit included in the BHA **55** for forming the wellbore **20** but can be a coiled tubing **17** when the BHA **55** is a radial jet drilling unit (with no drill bit but a nozzle assembly as described herein).

In some aspects, radial set drilling can be used to form tunnels **70a** and **70b** due to, for example, a diameter and length of such tunnels **70a** and **70b**. For example, tunnels **70a** and **70b** can approximately 1-2 inches in diameter, with lengths between, for example, 100 and 700 feet. Although FIG. 1 shows two tunnels **70a** as being formed in subterranean formation **40** and two tunnels **70b** as being formed in subterranean formation **42**, there can be more (or fewer) tunnels **70a** and **70b** formed in these respective formations **40** and **42** as desired based on, for example, formation depth, thickness, geological parameters, or otherwise. In processes in which the tunnels **70b** are formed subsequent to a chemical injection into the tunnels **70a**, a temporary zonal isolation device **83** (for example, a temporary packer) can be installed in the wellbore **20** to fluidly isolate the low permeability formation **40** from the wellbore **20**.

In the example of FIG. 1, subterranean formation **42** represents a relatively high permeability formation, and subterranean formation **40** represents a relatively low permeability formation. In this example, "high" and "low" permeability can be relative in that a low permeability formation, generally, is defined by a permeability value (or average permeability) of about or less than $\frac{1}{3}$ value of a permeability value (or average permeability) of the high permeability formation. In example implementations, for instance, the relatively high permeability formation **42** can have a permeability of about 1000 mD while the relatively low permeability formation **40** can have a permeability of about 200 mD.

FIG. 2A is another schematic diagram of the example well system **10** of FIG. 1 according to the present disclosure. As shown in this example diagram, tunnels **70a** (two or more) extend from wellbore **20** into the relatively low permeability formation **40**, while tunnels **70b** (two or more) extend from wellbore **20** into the relatively high permeability formation **42**. In this example, once formed, the tunnels **70b** can serve as injection pathways through which an injection fluid **71** can be circulated from the wellbore **20**, into the tunnels **70b**, and then into the relatively high permeability formation **42**. This injection process, in some aspects, can be completed prior to formation of the tunnels **70a** in the relatively low permeability formation **40**. Thus, as shown in FIG. 2A, the wellbore **20** is an injection well in which the injection fluid **71** (for example, gel or swellable particles) is introduced to affect both the high permeability formation **42** and low permeability formation **40**.

As shown in this example, permeability decrease areas **75** are created subsequent to the injection of the injection fluid **71** from the tunnels **70b** into the relatively high permeability formation **42**. As illustrated, these areas **75** can surround the tunnels **70b** of the relatively high permeability formation **42**, which is made possible by the injection from tunnels **70b** (rather than, conventionally, the injection wellbore **20** alone). If no tunnels **70b** were formed, the areas **75** would

not be as large as compared to the illustrated example where the tunnels **70b** have been formed (such as by radial jet drilling).

By injecting the injection fluid **71** from the tunnels **70b**, the illustrated well system **10** can treat both the high and low permeability formations **42** and **40**, respectively, in the same operation by increasing a water intake capacity of the low permeability formation **40** while reducing the water intake capacity of the high permeability formation **42**. While the tunnels **70b** allow for deeper migration of the injection fluid **71**, the tunnels **70a** formed (for example, after injection) in the low permeability formation **40** can effectively increase a contact area between injected water and a reservoir rock in the formation **40**.

FIG. 2B is another schematic diagram of a portion of the example well system **10** of FIG. 1 according to the present disclosure. This figure shows an example radial jet drilling operation that can be used to form, for example, tunnels **70a** and tunnels **70b**. In this example operation, subsequent to formation of the wellbore **20** (such as by a drill bit), a deflection shoe **93** can be installed in the wellbore **20** and a coiled tubing **17** can be run in the wellbore to a particular depth (for example, in formation **40** to form tunnels **70a**, or formation **42** to form tunnels **70b**).

As shown in this example implementation, a high pressure hose **80** is coupled to the coiled tubing **17** and ends in a jet nozzle **85**. In this example, the jet nozzle **85** includes forward jets **87** and backward jets **88**. A high pressure fluid is circulated through the coiled tubing **17** and high pressure hose **80** and ejected as high pressure fluid **87** from the forward nozzles **90** to erode and drill the subterranean formation **40** to form a tunnel **70a** as shown. The high pressure fluid is also ejected as high pressure fluid **88** from the backward nozzles **95** push the nozzle **85** forward (i.e., into the formation **40** away from the wellbore **20**) and to widen the formed tunnel **70a**.

FIG. 3 is a flowchart that shows an example method **300** for treating both high and low permeability formations according to the present disclosure. In some aspects, method **300** can be implemented by or with the well system **10** as shown in FIGS. 1, 2A, and 2B, including the high pressure fluid injection system shown in FIG. 2B. Method **300** can begin at step **302**, which includes logging a wellbore to determine a target location of a high permeability formation and a low permeability formation. For example, once wellbore **20** is formed (for example, with conventional rotary drilling techniques or otherwise), the BHA **55** can be replaced by a logging tool (or otherwise, a logging tool **55**) and the wellbore **20** can be logged for an injection profile. A target location can be determined by the interpretation of the log.

The target location can be a location in which heterogeneous formations—a high permeability formation and a low permeability formation—are adjacent or near each other along a depth of the injection wellbore **20**. In some aspects, the log, therefore, determines that the low permeability formation has a permeability of about $\frac{1}{3}$ or less of the high permeability formation.

In some aspects, subsequent to logging, an operational design for the remaining steps of method **300** can be implemented, such as through a virtual model of the geophysical environment and numerical simulation. By creating the operational design based on the virtual model and numerical simulation, the improved conformance control of the formations can be achieved.

Method **300** can continue at step **304**, which includes installing a deflector shoe at or near the target location and

milling a window through a wellbore casing and cement (if needed). For example, in the example of the wellbore **20** including a casing, a window can be milled (with a drill bit or milling equipment) using a deflection shoe to at least begin a lateral wellbore from which a tunnel can be formed at or near the target location.

Method **300** can continue at step **306**, which includes running a high pressure injection string into the wellbore to the high permeability formation of the target location. For example, radial jet drilling equipment can be installed (such as on a coiled tubing unit) in the wellbore **20** (subsequent to removal of injection tubing if present). The nozzle **85** can be run into the wellbore **20** to the target location of the high permeability formation **42** on the high pressure hose **80**.

Method **300** can continue at step **308**, which includes forming two or more tunnels into the high permeability formation with the high pressure nozzle. For example, the radial jet drilling system can form two or more (and even eight or more) tunnels **70b** in the high permeability formation **42**. Each tunnel **70b** can be, for example, 1-2 inches in diameter and between 100 and 700 feet in length. Subsequent to step **308**, the radial jet drilling equipment can be run out of the wellbore **20**.

Method **300** can continue at step **310**, which includes isolating the low permeability formation of the target formation. For example, temporary, zonal isolation devices can be installed to isolate a low permeability formation **40** against chemical injection so as not to damage the low permeability formation **40**.

Method **300** can continue at step **312**, which includes injecting a chemical fluid into the high permeability formation to reduce its permeability around the wellbore to decrease the water intake capacity. For example, a chemical fluid, such as gels and swellable particles, is injected through tunnels **70b** and into the high permeability formation **42**. In some example aspects, a volume of the injected chemicals can be about 0.02 to 0.10 pore volume of the high permeability formation **42**.

Method **300** can continue at step **314**, which includes running the high pressure injection string into the wellbore to the low permeability formation of the target location. For example, once the temporary zonal isolation is removed, the radial jet drilling equipment can be re-installed (such as on a coiled tubing unit) in the wellbore **20**. The nozzle **85** can be run into the wellbore **20** to the target location of the low permeability formation **40** on the high pressure hose **80**.

Method **300** can continue at step **316**, which includes forming two or more tunnels into the low permeability formation with the high pressure nozzle. For example, the radial jet drilling system can form two or more (and even eight or more) tunnels **70a** in the low permeability formation **40**. Each tunnel **70a** can be, for example, 1-2 inches in diameter and between 100 and 700 feet in length. Subsequent to step **316**, the radial jet drilling equipment can be run out of the wellbore **20**. At that time, the injection wellbore **20** can be used to alternate a water intake and distribution of injection water in the layered heterogeneous reservoir of the high and low permeability formations.

FIGS. 4A and 4B are virtual geological models of a well system that includes multiple tunnels formed in subterranean formations to treat both high and low permeability formations according to the present disclosure. For example, as noted, subsequent to logging, an operational design for method **300** can be implemented, such as through a virtual model of the geophysical environment and numerical simulation. By creating the operational design based on the virtual model and numerical simulation, the improved con-

formance control of the formations can be achieved. The virtual models **400** and **450** of these figures represent a conceptual geological model of an inverted five-spot well pattern (1 injector **406** and 4 producers **408a-408d**) that was generated to investigate the performance of a combination of radial jet drilling with chemical injection through method **300** for improving conformance of an injection well.

Virtual model **400** illustrates a permeability distribution of scale **402** (in millidarcys) of subterranean layers **404a**, **404b**, and **404c** with differing permeability distributions. The size of the virtual model **400** is 902.2×902.2×13 meters, and the number of grid blocks is 101×101×3. The thickness of three layers **404a**, **404b**, and **404c**, are 5, 5, and 3 meters, respectively. The permeability of the three layers **404a**, **404b**, and **404c**, are 300, 200 and 1000 mD, respectively. In this example, a vertical permeability is 0.1 times a horizontal permeability. The porosities of the three layers **404a**, **404b**, and **404c**, are 0.22, 0.21, and 0.25, respectively. The cross-flow between layers is suppressed by modifying the vertical transmissibility. All layers **404a**, **404b**, and **404c** have an initial water saturation of 0.25 for the numerical simulation.

As shown, the model **400** shows the injector **406** and two of the producers: **408a** and **408b**. Virtual model **450** shows the injector **406** and all four producers: **408a-408d**. Thus, for this inverted five-spot pattern, one injection well and four production wells were placed in the model. The injection well **406** is at the center of the model, and the four production wells **408a-408d** are at the four corners of the model. The injection well **406** is rate constrained and the rate is 500 m³/day, and the producers **408a-408d** are pressure constrained.

The virtual model **450** illustrates a water saturation distribution of scale **452** (in millidarcys) of subterranean layers **404a**, **404b**, and **404c**. Virtual model **450** has the same scale and characteristics as virtual model **400**. Simulations were conducted on the virtual models **400** and **450** to investigate the performance of a combination of radial jet drilling with chemicals injection for improving conformance of injection well as described in the present disclosure. Four cases were simulated. The first simulation (which excludes the combination and does not include tunnels formed with radial jet drilling nor injected chemicals) serves as a base for comparison. The second simulation includes four tunnels formed in each low permeability layer, which were formed after 36 months of water injection. The third simulation includes an injection of swellable particles into the high permeability layer to decrease its water intake after 36 months of water injection (but excludes tunnels formed from radial jet drilling).

The fourth case is a combination of case 2 and modified case 3 (and therefore is an implementation of method **300** and the present disclosure). Injection tunnels are first formed in the high permeability layer, and then chemicals were injected to decrease its permeability. In the fourth simulation, after the high permeability layer **404c** is treated, formation tunnels are drilled in the low permeability layers **404a** and **404b**.

In the example simulation of case four, four tunnels were drilled in each layer **404a-404c** using radial jet drilling technology. Each tunnel was 335 to 400 feet long in the low permeability layers **404a** and **404b** and about 120 feet long in the high permeability layer **404c**. The location of the formation tunnels in the low permeability layers and the area where the permeability decreases after injecting swellable particles if shown in the virtual model **400** (which is a cross-sectional view along the formation tunnels). The differing grayscale of the first and second layers **404a** and

404b, respectively, represents the space affected by the formation tunnels, while the differing grayscale area of the third layer **404c** represents the area of the high permeability layer where the injected chemicals were swept. In the simulations, the permeability of the portions of the model **400** located at the location of the tunnels were modified to 100 D, and the permeability of the portions of the model **400** affected by swellable particles were modified to one-tenth of the original permeability.

The virtual model **450** shows the water saturation distribution after 36 months water flooding by the injector **406**. The high-permeability layer **404c** has high water saturation and uniform swept since there is a homogeneous permeability distribution. But there is still a large area in the first and second low permeability layers **404a** and **404b** where the oil saturation is close to the initial saturation as shown by the scale **452**. After the injection water of the high permeability layer **404c** breaks through the production wells **408a-408d**, it can become difficult to expand the swept volume of water flooding in the low permeability layers **404a** and **404b** and reduce the oil saturation.

FIGS. 5-8 are graphs that illustrate water cut comparisons in a well system includes multiple tunnels formed in subterranean formations to treat both high and low permeability formations according to the present disclosure. Graphs **500**, **600**, **700**, and **800**, more specifically show information related to the four simulations described with reference to FIGS. 4A and 4B.

Graph **500** show the water intake changes due to the fourth simulation (using method **300** of the present disclosure). As shown, graph **500** includes x-axis **502** of time (month and year) and y-axis **504** of water intake of each layer (in m³/day). Curves **506a-506c** represent the base simulation for layers 1-3 (**404a-404c**), respectively. Curves **508a-508c** represent the fourth simulation for layers 1-3 (**404a-404c**), respectively. As shown, the average water intake of layers 1 and 2 (**404a** and **404b**) increased from 81.4 and 40.8 to 197.1 and 171.8 m³/day, respectively, and the average water intake of layer 3 (**404c**) decreased from 276.4 to 31.6 m³/day. The reduction of water intake in the high-permeability layer **404c** effectively reduces the invalid circulation of injected water; that is, the injected water quickly reaches the production well from the high-water-saturation channel in the high-permeability layer. The enlargement of the swept area of the low-permeability layer affects the change of water cut and oil production rate, and hence the total oil production.

Graph **600** show a comparison of simulated water cut changes between the four simulations previously described. As shown, graph **600** includes x-axis **602** of time (month and year) and y-axis **604** of water cut (by fraction of produced fluid). Curves **606-612** represent the water cut according to the four simulations, with curve **606** representing the base (or first) simulation, curve **608** representing the second simulation, curve **610** representing the third simulation, and curve **612** representing the fourth simulation.

Graph **700** show a comparison of simulated oil production rate changes between the four simulations previously described. As shown, graph **700** includes x-axis **702** of time (month and year) and y-axis **704** of change in oil production (in m³/day). Curves **706-712** represent the rate change of produced oil according to the four simulations, with curve **706** representing the base (or first) simulation, curve **708** representing the second simulation, curve **710** representing the third simulation, and curve **712** representing the fourth simulation.

11

Graph 800 show a comparison of simulated oil production total changes between the four simulations previously described. As shown, graph 800 includes x-axis 802 of time (month and year) and y-axis 804 of total oil production (in Mm^3). Curves 806-812 represent the total volume of produced oil according to the four simulations, with curve 806 representing the base (or first) simulation, curve 808 representing the second simulation, curve 810 representing the third simulation, and curve 812 representing the fourth simulation.

A number of implementations have been described. Nevertheless, it will be understood that various modifications may be made without departing from the spirit and scope of the disclosure. For example, example operations, methods, or processes described herein may include more steps or fewer steps than those described. Further, the steps in such example operations, methods, or processes may be performed in different successions than that described or illustrated in the figures. Accordingly, other implementations are 20 within the scope of the following claims.

What is claimed is:

1. A conformance control method, comprising:
identifying a target location of a wellbore formed from a 25 terranean surface to at least two subterranean formations, the at least two subterranean formations comprising a high permeability formation having a first permeability and a low permeability formation having a second permeability that is equal or less than one-third of the first permeability;

forming, with a radial jet drilling assembly, a first plurality of tunnels in the high permeability formation from the wellbore;

injecting, into the high permeability formation, a chemical fluid from the wellbore through the first plurality of tunnels;

expanding a sweep area of the injected chemical fluid by injecting the chemical fluid into the high permeability formation through the first plurality of tunnels;

forming, with the radial jet drilling assembly, a second plurality of tunnels in the low permeability formation from the wellbore subsequent to injecting the chemical fluid from the wellbore, through the first plurality of tunnels, and into the high permeability formation; and

increasing a contact area of an injection fluid in the low permeability formation with the second plurality of tunnels.

2. The conformance control method of claim 1, wherein each of the first plurality of tunnels is 1-2 inches in diameter and between 100 and 700 feet in length from the wellbore, and each of the second plurality of tunnels is 1-2 inches in diameter and between 100 and 700 feet in length from the wellbore.

3. The conformance control method of claim 1, wherein the chemical fluid comprises a gel.

4. The conformance control method of claim 3, wherein the chemical fluid comprises swellable particles.

5. The conformance control method of claim 1, comprising logging the wellbore.

6. The conformance control method of claim 5, comprising identifying the target location based at least in part on a log of the wellbore generated by the logging.

7. The conformance control method of claim 1, comprising injecting the injection fluid into the wellbore subsequent to forming the second plurality of tunnels in the low permeability formation.

12

8. The conformance control method of claim 1, wherein the first plurality of tunnels comprises between 2 and 8 tunnels, and the second plurality of tunnels comprises between 2 and 8 tunnels.

9. The conformance control method of claim 1, wherein a volume of the injected chemical fluid comprises between 0.02 and 0.10 pore volume of the high permeability formation.

10. The conformance control method of claim 1, comprising isolating, with a temporary zonal isolation device, the low permeability formation from the wellbore prior to injecting the chemical fluid from the wellbore through the first plurality of tunnels.

11. A well system, comprising:

a wellbore formed from a terranean surface to a target location comprising at least two subterranean formations, the at least two subterranean formations comprising a high permeability formation having a first permeability and a low permeability formation having a second permeability that is equal or less than one-third of the first permeability;

a radial jet drilling assembly configured to perform operations comprising:

forming a first plurality of tunnels in the high permeability formation from the wellbore; and
subsequent to an injection of a chemical fluid into the high permeability formation from the first plurality of tunnels, forming a second plurality of tunnels in the low permeability formation from the wellbore;

and
a fluid injection system configured to inject the chemical fluid into the high permeability formation from the wellbore through the first plurality of tunnels, wherein a sweep area of the injected chemical fluid is expanded by injecting the chemical fluid into the high permeability formation through the first plurality of tunnels, and a contact area of an injection fluid is increased in the low permeability formation with the second plurality of tunnels.

40 12. The well system of claim 11, wherein each of the first plurality of tunnels is 1-2 inches in diameter and between 100 and 700 feet in length from the wellbore, and each of the second plurality of tunnels is 1-2 inches in diameter and between 100 and 700 feet in length from the wellbore.

45 13. The well system of claim 11, wherein the chemical fluid comprises a gel.

14. The well system of claim 13, wherein the chemical fluid comprises swellable particles.

15. The well system of claim 11, comprising a logging system configured to perform injection profile logging of the wellbore.

16. The well system of claim 15, wherein the target location is identified based at least in part on a log of the wellbore generated by the logging system.

17. The well system of claim 11, wherein the fluid injection system is configured to inject an injection fluid into the wellbore subsequent to the formation of the second plurality of tunnels in the low permeability formation.

18. The well system of claim 11, wherein the first plurality of tunnels comprises between 2 and 8 tunnels, and the second plurality of tunnels comprises between 2 and 8 tunnels.

19. The well system of claim 11, wherein a volume of the injected chemical fluid comprises between 0.02 and 0.10 pore volume of the high permeability formation.

20. The well system of claim 11, comprising a temporary zonal isolation device positioned in the wellbore to fluidly

isolate the low permeability formation from the wellbore prior to injection of the chemical fluid from the wellbore through the first plurality of tunnels.
